UNITED STATES PATENT OFFICE

ALBERT DE CANIO, OF NEW YORK, N. Y.

DESIGN FOR A DISPLAY HOLDER

Application filed December 22, 1930. Serial No. 38,057. Term of patent 3½ years.

To all whom it may concern:

Be it known that I, ALBERT DE CANIO, a citizen of the United States, residing at New York, in the county of New York, State of New York, have invented a new, original, and ornamental Design for a Display Holder (Case B), of which the following is a specification, reference being had to the accompanying drawing, forming part thereof.

In the drawings:

Fig. 1 is a front elevation of the display holder showing my new design.

Fig. 2 is a side elevation of the same.

I claim:

The ornamental design for a display holder, as shown.

ALBERT DE CANIO.
